United States Patent Office.

WILLIAM H. WHITEHEAD, OF CHICAGO, ILLINOIS.

Letters Patent No. 69,879, dated October 15, 1867.

IMPROVEMENT IN GRATES FOR COOKING-STOVES.

The Schedule referred to in these Letters-Patent and making part of the same.

TO ALL WHOM IT MAY CONCERN:

Be it known that I, WILLIAM H. WHITEHEAD, of the city of Chicago, in the county of Cook, and State of Illinois, have invented certain new and useful Improvements in Stoves; and I do hereby declare that the following is a full, clear, and exact description thereof, reference being had to the accompanying drawings, making a part of this specification, in which—

Figure 1 is a transverse vertical section.

Figure 2, a longitudinal vertical section.

Figure 3, a top view of a portion of the grate detached, and

Figure 4 a front view of the lower end of one of the end plates of the fire-box.

Like letters refer to the same parts in all of the figures.

The nature of my invention consists in providing the back of the fire-box of a stove with a plate arranged or constructed to operate with an adjustable lower grate, so that that portion of it which is between the points of change in the position of the grate will be vertical, and the portion above that inclined backwards, such plate to be provided with rests or stops to prevent the tipping of the grate; in providing the back part of the fire-box, near the top, with an additional plate, or a part of the same plate as the back plate inclined forwards from the back plate, and providing such additional plate with hollow knobs or projections projecting inwards, and connected at the top by ledges, the plate and knobs being provided with air-holes; in making the grate adjustable in a novel manner; in providing one of the end plates with projections, to prevent the displacement of the grate, and in the combinations hereinafter set forth and claimed.

To enable others skilled in the art to make and use my invention, I will describe its construction and operation.

A represents a stove, of any suitable construction. In this stove I construct my fire-box. The front plate P has its upper half made solid, and its lower half grated; as shown at Q, fig. 2. The end plate G is beaded at the end where the side door is usually placed, and is provided with two holes, L and M, through which the shaft F of the bottom grate passes far enough to admit of a wrench or shaker being placed on its end, so as to shake down the ashes, and so also as to permit the closing of the side door. At the side of the opening L a bracket or projection e is placed, so that when the grate E is inserted and turned down to its place, it will not move so as to permit the opposite end to fall, either in ordinary use or when shaking the ashes. The lower hole M has a similar ledge or projection around the bottom and at one side for like purposes. The opposite end plate H, which, with all the others, is corrugated, has also two corresponding holes, I and J, made in the middle swell of the corrugations, and side openings or slots a and b are cut in opposite sides, so that the shaft O; at the end of the grate E, can be inserted. Both of these holes are provided with circular ledges j and k, and are provided with lips to insure the entrance of the grate. The back plate B' and C is cast in one piece, and so located that the lower part B' will stand perpendicular, the part B incline back, and the part C incline forward. At the upper end of the vertical portion a lug or projection, f, is cast, so that, in connection with projection or catch e of the grate, the grate will be prevented from turning. A similar projection, g, is made at the bottom. The upper portion C of the back plate is provided with hollow projections D, which are curved on the outer surface, and made oblong, as shown at fig. 1. In these projections two or more small vent-holes are made, and similar ones are made in the plate between them, which connect with the air-chamber T between the fire-box and the oven, and the top of the plate is provided with ledges or projections h connecting the oblate projections at the top. This arrangement forms cross-currents and eddies in the passage of the products of combustion, and also cross-currents of the air introduced from the back of the fire-box, which improves it materially as a gas-burner. I provide the stove, in which I place my fire-box, with upper feed-doors S, but as these are common to many stoves they need not be described, but in use will be found very desirable if not necessary when the grate is in its upper position. In other respects any convenient construction of the stove can be adapted to the use of my fire-box.

In operation for a winter stove the grate E is placed in the holes J and M, so that, in combination with the fixed grate Q, an open-grated fire-place is formed, and the draught is through the bottom and the front grates. For a summer stove, for either coal or wood, the grate is placed in the holes I and L, so that the front grate is

closed and the draught is only through the bottom grate E, and the fire-box made much shallower, so as to bring the fire up in close contact with the vessels placed on the top of the stove, and produce a great saving in fuel without changing the parts, except in position, and without the use of extra or additional grates, changing it from an open to a close fire-box. This change also prevents the stove from heating up the room in summer.

Having thus fully described my improved fire-box for stoves, what I claim as new, and desire to secure by Letters Patent, is—

1. The changeable revolving grate E, in combination with the end plates G and H, and front grate P Q for the purpose of changing the fire-box from an open to a close grate, substantially as specified.
2. The projection or lock c attached to the end plate G, substantially as and for the purposes set forth.
3. The back plate B B' and C, when constructed substantially as described, and so located that the upper portion C will incline towards the front, the middle portion B incline backwards, and the lower B' remain vertical, so as to admit of a change in position of the grate E, substantially as specified.
4. The combination and arrangement of the front grate P Q, back plate B B' C, and the end plates G and H, with an adjustable revolving bottom grate, E, constructed and operating substantially as specified.

WM. H. WHITEHEAD.
